UNITED STATES PATENT OFFICE.

GEORGE F. MEYER, OF SMITHTON, MISSOURI.

VENTILATOR.

1,175,002.

Specification of Letters Patent. Patented Mar. 14, 1916.

Application filed June 24, 1913. Serial No. 775,532.

To all whom it may concern:

Be it known that I, GEORGE F. MEYER, a citizen of the United States, residing at Smithton, in the county of Pettis and State of Missouri, have invented certain new and useful Improvements in Ventilators, of which the following is a specification.

This invention relates to ventilators, which are well adapted to be used in connection with windows or the like, while not necessarily restricted to such use, and has particular reference to a ventilator of this type which is adjustable whereby the desired amount of air may be admitted to a room or the like.

An important object of this invention is to provide a ventilator of the above mentioned character, which will afford a proper free passage of air into a room or the like without creating a draft.

A further object of this invention is to provide a ventilator of the above mentioned character, having screening means to prevent the passage of insects or the like into the room, such means being arranged within the apparatus whereby the same is thoroughly protected.

A further object of this invention is to provide a ventilator of the above mentioned character, which is simple in construction, compact in the arrangements of its parts, easy to operate, strong and durable.

Other objects and advantages of the invention will be apparent during the course of the following description.

In the accompanying drawings forming a part of this specification and in which like numerals are employed to designate like parts throughout the same, Figure 1 is an outer side view of the apparatus, Fig. 2 is a plan view of the same, Fig. 3 is a central longitudinal sectional view through the same, Fig. 4 is a perspective view of the movable casing or housing included in the apparatus, and, Fig. 5 is a similar view of a co-acting stationary casing included in the apparatus.

In the drawings, wherein for the purpose of illustration is shown a preferred embodiment of my invention, the numeral 6 designates a body portion or sash-rail, which is preferably formed of wood, although other material may be employed. Connected with one end of the body portion or sash-rail 6 is a cap 7, preferably formed of sheet metal, and attached thereto by screws 8 or the like.

Mounted upon the opposite end of the sash-rail 6, is a longitudinally adjustable cap 9 which may be moved outwardly so that the body portion or sash-rail 6 will properly fit the window. The adjustable cap 9 includes a longitudinal plate 10, having its free end bent in the form of a curved handle 11, as shown. The longitudinal plate 10 is provided with an elongated slot 12, receiving a clamping screw 13, or the like.

The body portion or sash-rail 6 is provided with a large longitudinal opening 14, for receiving the inner portion of a stationary casing 15, which is preferably formed of sheet metal. The outer portion of this stationary casing extends beyond the body portion or sash-rail and is closed by a perforated side plate 16, as shown. The ends of the casing 15 are provided with openings 17. The casing 15 is attached to the body portion or sash-rail 6 by means of screws 18 or the like. The inner side of the stationary casing 15 is entirely open, as shown.

Disposed within the stationary casing 15 is a reciprocating casing 19, including an imperforate inner side or valve 20, carrying a preferably rectangular open frame 21, which is provided with relatively large openings 22, as shown. Attached to the free end of the open frame 21 is a section of wire netting or gauze 23, to move with the same. Attention is called to the fact that the wire netting or gauze 23 is mounted wholly within the stationary casing 15 whereby it is protected from rain and the like, while the same serves to prevent insects from entering the house. The open frame 21 includes ends strips 24, having longitudinal slots 25, for receiving guide pins or screws 26, as shown, which positively limits the outward movement of the casing 19. The casing 19 is moved by a knob or handle 27, attached to the plate 20, as shown.

In the use, the apparatus may be installed within a window, so that the sash will engage the sash-rail 6, when lowered. The apparatus may be permanently attached to a sash, either the upper or lower, a door, or may be built into the side of the room. It is obvious that by moving the casing 19 the air passing into the room may be regulated, such air passing laterally through openings 22, whereby a draft is avoided.

It is to be understood that the form of my invention herewith shown and described is to be taken as a preferred example of the

same, and that various changes in the shape, size and arrangement of parts may be resorted to without departing from the spirit of the invention or the scope of the subjoined claim.

Having described my invention, I claim:—

In a ventilator; an outer relatively stationary casing adapted to be arranged in an opening in a support for projecting outwardly beyond the support for a substantial distance, said casing having air circulating openings in its ends, its top closed, its inner side open, and its outer side covered by a perforated protecting plate; an inner frame 10 mounted to reciprocate transversely within the casing and having its sides and ends provided with air circulating openings; an 15

imperforate plate secured to the inner side of the frame to move it for regulating the amount of air circulating through the openings in the frame and carrying a handle; a section of wire mesh secured to the outer open side of the frame and permanently retained within the outer casing to be protected thereby; and means to limit the inward movement of the frame with relation to the outer casing. 20 25

In testimony whereof I affix my signature in presence of two witnesses.

GEORGE F. MEYER.
